COMPOSITE RECORD ASSEMBLY

De Witt I. Conklin, Syracuse, N. Y., assignor, by
mesne assignments, to American Sales Book
Company, Inc., a corporation of Delaware

Application March 2, 1932, Serial No. 596,177

6 Claims. (Cl. 282—12)

This invention relates to improvements in record assemblies for manifolding purposes adapted for use in various forms of writing machines or for manual inscription. More particularly the invention relates to improvements in record supplies of the long continuous traveler type and embodying a plurality of continuous record strips with one or more transfer strips in interleaved manifolding or transfer relation therewith.

It is a general object of the invention to provide for record supplies of the class mentioned an improved binding arrangement for retaining the several strips in correct manifolding relation with each other and for maintaining them in predetermined alignment both laterally and longitudinally.

A further object of the invention is to provide for record supplies of the class mentioned an improved securing arrangement for retaining the strips in correct position and having a captive attachment for the securing device to hold it captive upon terminating its binding function and thus preventing its falling into the machine or into the record supplies or on the floor or in other ways becoming a nuisance.

Still another object of the invention is to provide an improved binder for composite record supplies of the class mentioned which is automatically released from the record strips upon severance thereof along the severance lines, but remains attached after such severance to the transfer strip, thus not only holding the binder captive and preventing its falling, but also functioning as a gripping device or handle for facilitating removal of the transfer sheet, and also holding the transfer sheets together in a unit in case more than one transfer sheet is employed.

According to another feature of the invention the transfer strip or strips are formed with a selective grip part preferably disposed at each of their severance lines whereby the transfer sheets upon severance from the supply may be selectively gripped for separation therefrom from the record sheets. An improved binding device is arranged at each of a plurality of points along the record assembly adjacent the weakened severance lines and connected thereto in an improved manner to maintain the strips in correctly assembled relation with each other and to be automatically released from connection with the record strips upon severance along the transverse weakened severance line. Also, when thus severed, the binder is held captive by a selective attachment to the transfer strips.

According to another feature of the invention,

the improved structure for effecting separation of the transfer sheets from the record sheets and also the improved manner of attachment of the binding devices are arranged so as to avoid mutilation of the record sheets in any manner, while at the same time the binders are effective for maintaining the strips in correctly assembled relation and are automatically released from the record strips upon severance thereof along the weakened severance lines.

Another object of the invention is to provide an improved binding means for composite record supplies of the class mentioned and improved means for separating the transfer from the record sheets in a simple and satisfactory manner susceptible of easy and expeditious performance.

Another object is to provide an improved construction of weakened severance lines for transfer or record strips so as to assure their accurate and easy severance to provide selective grip parts or tabs.

Other objects of the invention will be in part pointed out in the following detailed description showing certain illustrative but preferred embodiments of the invention and will be in part obvious in connection therewith.

The invention accordingly comprises the features of construction, combinations of elements and arrangement of parts, which will be exemplified in the construction hereinafter set forth and the scope of the application of which will be indicated in the claims.

For a more complete understanding of the nature and objects of the invention reference is had to the following detailed description of the invention and to the accompanying drawings, in which

Fig. 1 is a perspective view of a composite record supply embodying the invention;

Fig. 2 is an enlarged perspective view of a set or section of sheets severed from the supply, the sheets being separated and shown diagrammatically;

Fig. 3 is a plan of the manifolding assembly, parts being broken away to disclose the transfer strip, and

Fig. 4 is a view similar to Fig. 2, but disclosing a modified form of the invention.

One of the important embodiments of the invention is disclosed in Figs. 1, 2 and 3 to which reference is made for a detailed description thereof. According to this embodiment, a plurality of record strips 10 of the long, continuous, traveler type are relatively superposed or interleaved with each other in manifolding relation. These

record strips may be made of material ordinarily employed for this purpose such as paper, and one or all of the strips may be provided with a longitudinal series of inscription receiving blank forms 11, the blank forms of the different strips being in superposed register or alignment with each other thus providing sets of forms for the simultaneous reception of inscriptions.

In relatively superposed or interleaved relation with the record strips 10 are transfer strips 12, preferably also of the long, continuous, traveler type, and being substantially co-extensive in length with the record strips. While this is a preferred form of applying the transfer strips, it will be understood that these strips need not, for all purposes, be continuous, but may be divided at longitudinal intervals which is within the purview of the invention. While two transfer strips 12 are shown, it will be understood that the number may be varied from one up to the requisite number to make the desired number of copies. Two transfer strips are herein shown interleaved in transfer relation with three record strips for convenience of disclosure.

25 A convenient manner of forming the assembly of record and transfer strips interleaved as described is to fold said assembly transversely as indicated at 13 so as to provide a zigzag folded supply pack 14 which is very convenient for storing, handling, shipping, etc., and for storing in position for use in manifolding machines such as typewriters, autographic registers, etc.

At each of a plurality of equally longitudinally spaced points along the composite manifolding assembly, the record strips 10 are formed with transversely extending severance lines 15. These severance lines may be weakened in any desired manner to facilitate severance of the record strips therealong; this weakening may be accomplished 40 by perforating or scoring the strips in a manner known in the art. As shown, these severance lines 15 may be positioned co-incident with the fold lines 13. They are also preferably positioned between the adjacent inscription receiving areas 45 or blank forms 11, thus dividing each of the record strips into a longitudinal series of record sheets or leaves 16. These individual record sheets are thus arranged in a series of sets or groups, each set including a plurality of record 50 sheets relatively superposed with each other.

In the embodiment shown the transfer strips 12 also are each formed with transverse severance lines 17 which may also be weakened to facilitate severance. The severance lines 15 and 17 of the record and transfer strips are preferably as shown 55 arranged in groups wherein the different severance lines are near to each other whereby the entire assembly may thus be severed at the same time along any one of these groups of severance lines. However, the severance lines of one of the sets of strips, that is, either the record strips 10 or the transfer strips 12, may jut ahead or be displaced longitudinally from the severance lines of the other set so as to provide selective grip 60 formations whereby one of the sets of strips may be gripped to the exclusion of the other set for separating the strips or sheets from each other, as more fully described below in one illustrative embodiment.

70 As clearly shown in Figs. 2 and 3, the selective grip formations may be provided by longitudinally displacing or deflecting the appropriate severance lines either throughout their entire extent or for only a portion of the length thereof.

75 In the embodiment shown, this is accomplished

by longitudinally deflecting a portion of the severance lines 17 of the transfer strips 12 as indicated at 18. As shown, this deflected part is positioned approximately at the longitudinal center line of the transfer strips, although it will be understood that for some purposes it might be arranged at a different point along the severance lines and on the severance lines 15 of the record strips instead of those of the transfer strips. The severance lines 17 also divide the record strips 12 into a longitudinal series of transfer sheets or leaves 19 similar in size to the record sheets 16 and interleaved with the latter in transfer position therewith.

Thus, with the structure of severance lines 17 as described, each of the transfer sheets 19 is provided with a selective grip part 20 which in the embodiment shown is in the form of a tab projecting longitudinally from one set of sheets into the next adjacent set. Also, the transverse edge 20 of each transfer sheet 19 opposite to the selective grip tab 20 thereof, is, by means of this deflected severance line provided with a recess or longitudinally displaced margin 21. This recess, as will be readily understood, will not be completely 25 formed until the severance of the line is completed. It will be clear that the grip tabs 20 may be positioned at the tops or leading ends of the record sheets or leaves 16, as shown, or they may equally as well be placed at the opposite or 30 bottom ends thereof.

For the purpose of assuring a clean and perfect severance along the deflected section 18 of the severance line 17, said deflected portion is preferably weakened to a greater extent than the remainder of the severance line. This increased weakening will assure the tearing of the strip along its deflected path, which might not always occur in case the deflected portion were not additionally weakened or of special construction. 40 Also, in order that the selective grip tab may be securely attached to its sheet 19, its base or part thereof attached to the sheet is of full strength and there is no perforating or weakening at this point. The tendency therefore during the tearing 45 operation is to part along the weakened line 17 and around the tab at the additionally weakened part 18.

An effective manner of weakening the deflected section 18 of the severance line is shown in Fig. 3. According to this form there are two elongated incisions 22 delineating the projecting side of the tab 20. Each incision preferably extends all the way through the material of the strip, being cleancut therethrough. The opposite extremities of the incisions 22 lie adjacent to the perforated sections 17 of the severance line, but do not join the latter, thus leaving short integral parts 23 of the strip between the adjacent sections 17 and 18 of the severance line. A similar integral part of the strip may be provided as at 24 between the adjacent ends of the incisions 22. These integral sections 23 and 24 provide supports for the selective grip tab 20 to maintain the latter in position until the strip is severed. This avoids displacement of the tabs 20 at all times before and after assembly of the transfer strips with the record strips until the severing operation. It will be noted also that the integral supporting sections 23 at both sides of the grip tab 20 function to support the parts of the transfer strip intercepted between the weakened lines 17 and the slits 22, and lying in the angles between these weakened lines and slits. When severance occurs the integral parts 23 and 24 are readily severed, thus as-

suring parting of the strips along deflected line 18 and assuring a clean margin of the grip tab 20. The integral tab supporting parts 23 are sufficiently narrow to permit easy severance, say, about one-eighth of an inch, while the part 24 may be possibly a bit shorter, say, about three thirty-seconds of an inch.

As mentioned the transverse severance lines 15 and 17 of the record and transfer strips are aligned with each other depthwise of the assembly but the deflected parts 18 are out of alignment both with the lines 15 and the lines 17. The end sections 17 of the severance lines 17 and 18 extend entirely to opposite edges of the transfer strip and are aligned depthwise of the assembly at the opposite assembly marginal or edge portions with each other. This aligned arrangement of the severance lines assures the correct starting of the tearing operation along the respective severance lines, whether such tearing is started at one side of the assembly or at the other side thereof. The grip tab 20 is supported and held in position by the integral supporting section 24 and the parts of the strip positioned in the angles 25 between the lines 17 and slits 22 are supported and retained in position by the integral supporting sections 23, thus avoiding the tendency of these parts to become displaced or frayed during handling or usage. Since the supporting sections 23 are in direct alignment with the weakened lines 17 and positioned directly between the latter and the slits 22, the severance of these sections 23 during the tearing operation is assured. Also the binder 25 being in direct transverse alignment with the weakened lines 17 and with the supporting sections 23, severance of said supporting sections 23 is further made easy and sure.

It will be observed that the incisions 22 are curved or arcuate in form and are positioned to provide obtuse angles between the extremities thereof and the line of the sections 17. This provides a tab having quite a flat or obtuse edge, which is effective for the purpose herein disclosed and facilitates severance along the predetermined severance line provided by the sections 17 and 18.

It will be noticed that the severance lines 15 of the record strips 10 are longitudinally displaced from the deflected sections 18 of the severance lines 17. In the embodiment shown, the severance lines 15 preferably extend straight across the record strips. For the purpose of maintaining the record and transfer strips in correctly aligned position in the assembly at all times a plurality of binders or securing devices 55 are provided at a series of points along the assembly. These binders, as shown, are in the form of filaments extending through the strips of the assembly. These filamentary binders may be in the form of textile threads, or light wires, being shown as staples 25, and having two arms the ends of which are bent over as at 26 to retain them in position.

An important feature of the invention resides in binding the strips together so that the binding devices are released from their attachment with one set of strips, such as the record strips, when the assembly is severed along the severance lines while at the same time the binders are held captive by the other set of strips such as the transfer strips in the embodiment shown. Thus, the filamentary binders 25 are attached to the record strips 10 at or co-incident with the severance lines 15 thereof. Therefore, as is herein shown, the filamentary binders 25 pass directly through the strips 10 directly on the severance lines 15 there-

of, while they pass through the transfer strips 12 at points removed from the severance lines 17 thereof.

As shown, the filamentary binders 25 pass through the carbon or transfer strips 12 at points within the vicinity of the respective grip tabs 20, being thus attached thereto at a point removed from the deflected portion 18 of the severance line. This provides a captive attachment for captivating or holding the binder 25 after severance of the strips so as to prevent the binder from falling into the writing machine or otherwise becoming displaced.

When a record is made upon the top or original sheet of the forward set of sheets 16 by a typewriting machine or in any other manner, the inscription is transferred to the underlying record sheets by the transfer sheets. The inscribed set of sheets is then severed either by use of a severing edge or blade, or by simply exerting a tearing pull upon the strips directed along the severance lines 15 and 17. Thus, all of the inscribed sets of sheets are severed at a single operation from the assembly. At the same time the binder 25 is released from its attachment with each of the record sheets by virtue of being placed coincident with the respective severance lines 15, as described. This release of the connection between the binder 25 and the record strips is thus automatically accomplished quickly and easily. Also, this is accomplished without any mutilation whatever of the record sheets.

Severance of the strips as described does not, however, release the binders 25 from their attachment with the transfer sheets. They continue to be held by the attachment thereof apart from the deflected part 18 of the severance lines 17. The severed transfer sheets are thus permanently held together by the binder and may thus be handled as a unit. Also, the binder 25 after removal of the record sheets projects slightly at opposite surfaces of the record sheets thus providing a convenient grip or handle facilitating grip engagement with the grip tabs 20.

When the set of record and transfer sheets is thus severed from the composite assembly, the transfer sheets can be separated from the record sheets by a very simple operation. This is accomplished by gripping the transfer sheets at the projecting tabs 20 thereof and at the same time gripping the record sheets in line with the apertures 21 formed at the opposite edges of the transfer sheets, whereupon the sheets are readily pulled apart and separated into two groups.

It will be noticed that the selective grip portions or tabs 20 are always held together as a unit by the binders 25, whereby they may be quickly and easily grasped for separating the carbon sheets from the record sheets. This feature is of considerable advantage, especially when there is a large number of transfer sheets, as it enables the operator to quickly and surely grasp all of the tabs, thus avoiding the probability of leaving any of the carbon sheets behind in interleaved position with the record sheets. The stripping operation or separation of the sheets into different sets is in this manner considerably facilitated.

Referring more particularly to Fig. 3, it will be noted that the binders or staples 25 are positioned directly opposite to and in longitudinal alignment with the deviating or deflected portions 18 of the transverse, weakened severance lines, and directly at the selective grip tabs or extensions 20. This arrangement binds the strips 75

together at the tab extensions so as to greatly facilitate severance around the deviating portions 18 at each time that the composite record assembly is severed along a group of severance lines. Correct severance to form the extending grip tabs is thus assured. Furthermore, it will be noticed that the binders 25 are adjacent to and substantially in transverse alignment with the integral sections 23 of paper which are positioned between the adjacent ends of the severance lines 17 and the ends of the deviating portions 18. This arrangement also assists in the severance of these short, integral sections when the assembly of strips is being severed along the severance lines. In other words, the arrangement of these parts is such as to assure tearing of the strips along the weakened lines provided therefor and to avoid accidental severance of the tab extensions during the tearing operation.

20 While carbon or transfer strips of the one-time type are herein disclosed as being interleaved with the record strips to form the complete unitary manifolding assembly, it is to be understood that the invention is applicable to strip assemblies of different types, and either with or without separate transfer strips or sheets, or other inscription transfer means. However, the invention is especially well adapted to the form of composite record supply herein particularly disclosed as it very materially speeds up and otherwise facilitates the use of this form of record supply in various forms of writing and inscribing machines, or for hand inscription independently of any machine.

30 35 While the protruding edges of the selective grip tabs 20 are herein disclosed as being oval, they may be of other oblong form preferably with the major dimension extending transversely of the strip. They could also be circular in contour or square or triangular, but the oblong form is preferred as it promotes clean and easy severance, is less likely to become detached or displaced, and does not project so far into the next adjacent sheet.

40 45 Referring to the embodiment of the invention shown in Fig. 4, it will be observed that the general construction and arrangement of the records strips 10^a and interleaved relatively superposed transfer strips 12^a are substantially the same as described in detail above, in connection with Figs. 1, 2 and 3. In this view, corresponding parts are designated by the same reference numerals with the addition of the index "a". The record and transfer strips of the assembly are secured together by binders 25^a in the manner above described so that each individual binder is released from its attachment from the record strips when the latter are severed along their weakened severance lines, while said binder is held captive by its attachment to the transfer strips after severance.

50 55 In this embodiment, however, one or more of the strips, preferably the record strips, are arranged to provide carrier belts for the remainder of the strips. While all three of the record strips are herein shown as being constructed in the form of carrier belts, one of the strips may suffice for this purpose. Of course, it will be understood that the blank forms may be omitted from the carrier belt which would then ordinarily not be utilized to receive a record inscription.

60 65 The carrier belt 10^a as shown, may be formed with a marginal extension or feed band 27 extending longitudinally of the assembly. These marginal extensions may, as shown, be positioned at

both longitudinal edges of the assembly and each is provided with a longitudinal series of feeding apertures 28 for receiving the feeding devices, such as the teeth of sprocket wheels commonly used in the teletype form of writing apparatus. These apertured feed bands 27 shown in Fig. 4 may be disposed laterally beyond the adjacent longitudinal edges of the other strips of the assembly.

While the advantages of the invention above referred to in connection with Figs. 1, 2 and 3 obtain also in the embodiment of Fig. 4, there is an additional advantage in the latter form because the feed bands 27 and the apertures thereof are always accurately maintained in correct alignment with each other so that the feeding of the record is more accurately and surely accomplished, this being an important consideration in the teletype apparatus.

In the embodiment of the invention disclosed in Fig. 4, as in the other embodiment described, it is preferable that the respective severance lines 15^a and 17^a extend substantially to the respective strip edges. Therefore if the feed bands 27 are to form permanent parts of the strips, the lines 15^a will preferably extend entirely across said feed bands. If it is desired to sever the feed band after it has served its feeding function, the longitudinal edge or edges of each strip may be regarded as being disposed next to the respective feed band. In any case the lines 15^a and 17^a are substantially aligned with each other depthwise of the assembly at the marginal or edge portions of the assembly, thus promoting the correct starting of the severing operation as referred to above. The result is the same in the different embodiments.

It will be understood that the showing of Fig. 4 as well as that of Fig. 2 is partially diagrammatic, the record and transfer strips being shown as separated from each other to reveal the structure and arrangement, while the binders or staples are shown as being unduly elongated. In practice the strips ordinarily lie in close contact with each other and the binding staples are only of sufficient length to extend through the assembly, the opposite attaching ends of the staple lying in close engagement with the assembly faces.

Since certain changes may be made in the above construction and different embodiments of the invention could be made without departing from the scope thereof, it is intended that all matter contained in the above description or shown in the accompanying drawings shall be interpreted as illustrative and not in a limiting sense.

For example, insofar as the unitary or group separation of the transfer strips from the record strips is concerned, the group of transfer strips could be attached together independently of the attachments for the record assembly herein particularly described. In this event the transfer strips would remain permanently attached in a group after severance along any group of severance lines, whereupon they could be separated as an attached group from interleaved relation with the record strips.

Having described my invention what I claim as new and desire to secure by Letters Patent is:—

1. A composite record assembly including, in combination, a plurality of record strips and at least one transfer strip relatively superposed in manifolding relation and each having similarly longitudinally spaced transverse weakened severance lines arranged in groups for simultaneous severance of the strips therealong, said severance

- lines of each group being in alignment with each other depthwise of the assembly, said transfer strip severance line of each group having parts longitudinally deviating from the other parts thereof and from other lines of the same group so as to provide, upon severance along the respective severance lines, a longitudinally protruding selective grip extension narrower than the strips and inwardly spaced from each of the longitudinal assembly edges, said deviating parts of the transfer strip severance lines being weakened to a greater extent than said other parts thereof and being spaced at opposite ends from said other parts of the lines to form short, supporting integral strip sections positioned substantially in alignment with said other parts of the lines and between the latter and said deviating part so as to provide supports for the parts of the strip lying between the adjacent angularly disposed parts of the weakened severance lines, and a binder at each group of severance lines binding the strips together but spaced from said longitudinally deviating line part and being positioned directly at said grip extensions and substantially in transverse alignment with said integral sections and lying directly in the line of said other line parts.
2. A composite record assembly including, in combination, a plurality of record and transfer strips relatively superposed in manifolding relation and each having similarly longitudinally spaced transverse, weakened severance lines each of which extends substantially to each of the opposite longitudinal edges of its respective strip at both of the opposite longitudinal edge portions of the assembly, said severance lines being arranged in groups for simultaneous severance of the strips therealong, said severance lines of each group being in alignment with each other depthwise of the assembly at both said longitudinal assembly edge portions and at end sections thereof extending for a distance inwardly from each assembly edge portion, certain but not all of the said severance lines of each group having parts thereof which are spaced inwardly from each longitudinal assembly edge and positioned inwardly of said end sections, longitudinally deviating from other parts thereof and from other lines of the same group so as to provide, upon severance along the respective severance lines a longitudinally protruding, selective grip extension narrower than the strips and spaced inwardly from both longitudinal edges thereof, said deviating parts of the respective severance lines at each of the opposite lateral edges of said grip extension being weakened to a greater extent than said end sections of said lines, and a binder at each group of severance lines binding the strips together and positioned directly at said grip extension but being longitudinally spaced from said longitudinally deviating parts of the weakened severance lines.
3. A composite record assembly including, in combination, a plurality of record strips and at least one transfer strip relatively superposed in manifolding relation with each other and each having similarly longitudinally spaced transverse weakened severance lines each of which extends substantially to one longitudinal edge of its respective strip at one longitudinal edge portion of the assembly, said severance lines being arranged in groups for simultaneous severance of the strips therealong, said severance lines of each group being in substantial alignment with each other depthwise of the assembly at said longitudinal assembly edge portion so as to as-
- sure correct starting of strip severance, said transfer strip severance line of each group having parts thereof longitudinally deviating from other parts and longitudinally deviating from record strip weakened lines of the same group so as to provide, upon severance along the respective severance lines, a longitudinally protruding selective grip extension, narrower than the strips, said deviating parts of the transfer strip severance lines each having an elongated slit to provide greater weakening than said other severance line parts, at least one end part of said deviating slotted line being positioned in transverse alignment with said other line parts but spaced therefrom to form a short, integral strip supporting section positioned substantially in transverse alignment with said other line parts, and between the latter and said slotted part, said slit terminating outwardly along said grip extension to provide a second integral strip-supporting section for the outer part of said extension, and a binder extending through the strips at each group of severance lines binding the strips together and positioned directly on the severance lines of the record strips but spaced from said deviating parts, said binders being positioned directly at and in longitudinal alignment with the grip extensions and in substantial transverse alignment with said other line parts and with said first mentioned integral strip-supporting sections.
4. A carbon strip for manifolding assemblies having a plurality of longitudinally spaced, transverse weakened severance lines, each of said severance lines having a deviating part delineating a tab extension, said deviating part being positioned intermediate the ends of the severance line and being weakened by slits in the strip to a greater extent than the other or end portions of the respective severance line, said deviating part of each severance line having the opposite end parts thereof disposed at an angle to adjacent parts of the line and positioned in substantially transverse alignment with said adjacent parts and being spaced at the opposite end parts thereof from the adjacent parts of the line to form short integral supporting sections of strip material which are positioned substantially in alignment with the respective adjacent parts of the line and between the latter and said deviating part so as to provide supports for the parts of the strip lying between the adjacent angularly disposed parts of the weakened severance line, and an additional integral strip section between adjacent slits of said deviating part and spaced from said first mentioned integral sections to provide a tab extension support.
5. A composite record assembly including in combination, a plurality of record and transfer strips relatively superposed in manifolding relation, and each having similarly longitudinally spaced transverse weakened severance lines each of which extends substantially to one longitudinal edge of its respective strip at one longitudinal edge portion of the assembly, said severance lines being arranged in groups for simultaneous severance of the strips therealong, said severance lines of each group being substantially in alignment with each other depthwise of the assembly at said longitudinal assembly edge portion and at end sections thereof extending for a distance inwardly from said assembly edge portion, certain but not all of the said severance lines of each said group having parts thereof which are relatively short as compared to the assembly width, longitudinally deviating from

other parts thereof and from other lines of the same group so as to provide, upon severance along the respective severance lines, a longitudinally protruding selective grip extension on each strip with the deviating line part, said grip extensions being narrower than the strips, said deviating parts of the respective severance lines at the lateral edge portions of the respective grip extensions next to the said end sections of the severance lines being weakened for severance about the grip extensions to a greater extent than said end sections of said lines, and a binder at each group of severance lines positioned substantially upon certain of said severance lines and binding the strips together, said binders being positioned directly at the respective said grip extensions but being spaced from the respective longitudinally deviating parts of the weakened severance lines.

6. A composite record assembly including in combination, a plurality of record and transfer strips relatively superposed in manifolding relation and each having similarly longitudinally spaced transverse weakened severance lines each of which extends substantially to one longitudinal edge of its respective strip at one longitudinal edge portion of the assembly, said severance lines being arranged in groups for simultaneous severance of the strips therealong, said severance

lines of each group being substantially in alignment with each other depthwise of the assembly at said longitudinal assembly edge portion and at end sections thereof extending for a distance inwardly from said assembly edge portion, certain but not all of the said severance lines of each said group having parts thereof which are relatively short as compared to the assembly width, longitudinally deviating from other parts thereof and from other lines of the same group so as to provide, upon severance along the respective severance lines, a longitudinally protruding selective grip extension on each strip with the deviating line part, said grip extensions being narrower than the strips, said deviating parts of the respective severance lines at the lateral edge portions of the respective grip extensions next to the said end sections of the severance lines, including elongated slits in the strips to weaken them so as to facilitate severance about the grip extensions, and a binder at each group of severance lines positioned substantially upon certain of said lines and binding the strips together, said binders being positioned directly at the respective said grip extensions but being spaced from the respective longitudinally deviating parts of the weakened severance lines.

DE WITT I. CONKLIN.
